UNITED STATES PATENT OFFICE.

JAMES M. WRIGHT, OF TAMA, IOWA.

DISPLAY-CASE.

1,228,510.

Specification of Letters Patent.

Patented June 5, 1917.

Application filed May 25, 1916. Serial No. 99,870.

To all whom it may concern:

Be it known that I, JAMES M. WRIGHT, a citizen of the United States, residing at Tama, in the county of Tama and State of Iowa, have invented certain new and useful Improvements in Display-Cases, of which the following is a specification.

This invention relates to improvements in show cases, more particularly to the class 10 of show cases in which a plurality of drawer-like receptacles are employed and adapted to be independently inserted into and removed from the show case and provided with perforated or reticulated bottoms providing communication between the body of the casing and the interior of the receptacles or drawers.

With these and other objects in view, the invention consists in certain novel features 20 of construction, as hereinafter shown and described and then specifically pointed out in the claim; and in the drawings illustrative of the preferred embodiment of the invention—

25 Figure 1 is a longitudinal sectional elevation;

Fig. 2 is a transverse section;

Fig. 3 is a plan view in section on the line 3—3 of Fig. 2;

30 Fig. 4 is a detached perspective view from beneath of one of the drawer-like receptacles;

Fig. 5 is a sectional detail illustrating a modification in the construction.

35 Corresponding and like parts are referred to in the following description and indicated in all the views of the drawings by the same reference characters.

The improved device comprises a casing 40 or shell including vertical corner members 10, an upper frame formed of inclosing members 11, a base represented as a whole at 12, and an intermediate frame formed of horizontal members 13 connected to the vertical corner members 10. The space between the upper frame 11, the corner members 10, and the intermediate frame members 13 is occupied by panels 14 of glass or the like, while the space between the base 12, the corner members 10, and the intermediate frame members 13, is occupied by panel members 15 also preferably of glass. The base 12 supports a bottom member 16, as shown. The intermediate frame members 13 are connected at suitable intervals by transverse supports 17. The end portions of the inter-

mediate members 13 are provided respectively with inwardly directed supporting ribs 18, while the transverse members 17 are provided with similar supporting ribs 19. 60

The drawer-like receptacles are each constructed with sides 20, forward ends 21 and rear ends 22, the sides 20 having guide channels to engage the ribs 18—19, as shown in Fig. 1. The rear end 22 of each receptacle 65 fits between the rear portion of the upper frame 11 and the rear portion of the intermediate frame 13 and is preferably provided with a lip-like projection 24 to engage over the rear faces of the frame members, while the forward end 21 of each receptacle is of less height than the rear end 22, while the upper edges of the sides 20 are curved upwardly and rearwardly, as shown in Fig. 2. The bottom 25 of each of the 70 receptacles is preferably formed of sheet metal and provided with a plurality of openings 26, the openings providing communication between the interiors of the receptacles and the interior of the casing below the receptacles so that the atmosphere freely circulates throughout the entire interior of the show case, or both above and below the receptacles and likewise throughout the interior of the receptacles. 80

The improved device is designed more particularly for holding cigars and similar articles in convenient position for access by the purchaser or the salesman and likewise displayed constantly under glass and thereby protected from deterioration. When employed for displaying cigars and like commodities which are required to be maintained in moistened or humid condition the openings 26 will be found of great advantage, as they permit the moist air from the humidors, when employed, to freely circulate throughout the entire interior of the show case including the interiors of the receptacles. The improved device may be of 90 any required size, or of any suitable material, and any required number of the receptacles may be employed and of any required size or form. 95

The improved device may likewise be employed for holding and displaying goods other than cigars, such as candy and the like, and the walls of the receptacles may be varied in height to adapt the device to the form or condition of the goods to be displayed. 105

The openings 26 may be of any size or 110

form and may be arranged in parallel relation longitudinally of the drawers as shown at the left in Fig. 3, or transversely of the drawers, as shown at the right in Fig. 3. If preferred the members 17 may be in the form shown in Fig. 5 to bring the sides 20 of the receptacles closer together. The rear of the casing below the drawer-like receptacles will preferably be provided with 10 sliding closures represented conventionally at 27.

Having thus described the invention, what is claimed as new is:

15 A display case including a cabinet having inclosing walls and provided with intermediate end frame members and an intermediate side frame member arranged in a horizontal plane, said intermediate end frame members and side frame member being provided with enlarged heads directed inwardly 20 of the walls of the cabinet, the inner face of the head portion of the side frame mem-

ber being unobstructed and the inner faces of the end frame members being provided with inwardly extending guide ribs, a plurality of intermediate horizontal supports arranged within the cabinet between the end frame members and engaging the side frame member at one end, each end frame member and each intermediate support being provided with oppositely disposed guiding ribs, a plurality of drawers slidably mounted within the casing and provided with guiding channels adapted to receive the guiding ribs, the sides of the drawers adapted to 35 slidably engage the body portions of the end frame members and the intermediate frame members and to bear at one end against the inner face of the side frame member, whereby the drawers are maintained in spaced relation to the walls of the cabinet to permit the circulation of air around the drawer.

In testimony whereof I affix my signature.

JAMES M. WRIGHT. [L. s.]
